(57) **CLAIM**

The ornamental design for a nuclear magnetic resonance system, as shown and described.

DESCRIPTION

FIG. 1 is a front perspective view of a nuclear magnetic resonance system showing my new design;
FIG. 2 is a rear perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is bottom plan view thereof; and,
FIG. 9 is a second front perspective view thereof, showing the chair portion in an alternative position.
